DESIGN FOR A LUMINAIRE

Frederic C. Winkler, Lakewood, and Carl F. Haas, Cleveland, Ohio, assignors to Westinghouse Electric & Manufacturing Company, a corporation of Pennsylvania

Application December 14, 1940, Serial No. 97,313

Term of patent 14 years

To all whom it may concern:

Be it known that we, Frederic C. Winkler and Carl F. Haas, citizens of the United States, residing, respectively, at Lakewood and Cleveland, in the county of Cuyahoga and State of Ohio, have invented a new, original, and ornamental Design for Luminaires, of which the following is a specification, reference being had to the accompanying drawing, forming part thereof, in which the single figure of the drawing is a per-

spective view of a luminaire embodying our new design, the concealed side and end being the same as those shown.

The dominant features of our design reside in the parts shown in solid lines.

We claim:

The ornamental design for a luminaire, as shown and described.

FREDERIC C. WINKLER.
CARL F. HAAS.
